UNITED STATES PATENT OFFICE.

WILLIAM C. WATERS, OF SAN FRANCISCO, CALIFORNIA.

BRAKE FOR WINDING OR HOISTING ENGINES.

SPECIFICATION forming part of Letters Patent No. 281,810, dated July 24, 1883.

Application filed May 21, 1883. (No model.)

To all whom it may concern:

Be it known that I, WILLIAM C. WATERS, of the city and county of San Francisco, State of California, have invented an Improvement 5 in Brakes for Winding or Hoisting Engines; and I hereby declare the following to be a full, clear, and exact description thereof.

My invention relates to certain improvements in brakes for hoisting engines; and it 10 consists of certain details of construction which will be more fully explained by reference to the accompanying drawings, in which—

Figure 1 is a side elevation of my brake, showing a section of one shoe and the blocks. 15 Fig. 2 is a view of the back of the brake. Fig. 3 is a transverse section.

A A' are cast or wrought iron brake-shoes, which are curved to the same arc as that of the wheel B, upon which they are intended to 20 act. These shoes have channels or grooves C formed in their curved faces to receive the wooden blocks which form the frictional surface. These blocks may be made short and of almost any available wood. They are cut 25 to fit into the channels, and may be dropped in, the first one resting upon the flange at the bottom of the channel, and the others one above another until the channels are full.

Plates D fit across the upper ends of the 30 channels, and when all the blocks are in place they may be secured by screws, so as to hold the blocks firmly, when they will also be retained, partly by their proximity to the surface of the wheel, but more particularly be- 35 cause they form the inner curve of the shoe and cannot move toward the center without binding more closely.

The shoes A A' are suspended upon bars or 40 links E, the lower ends of which rest upon foundation-blocks F, which are united by rods G. The backs of the brake-shoes are flanged at their edges, so that the single-bar E, which 45 supports each shoe, lies between these flanges, and bolts or shafts H H' pass through the upper ends of the bars and through the flanges horizontally at or near their centers, so that the 50 shoes turn freely upon these bolts. Vertical bars I are fitted upon the ends of the bolts or shafts H, so as to stand outside the edge of the wheel rims and rods J, extending across the sides of the wheel just above and

below the center, as shown. This causes the brakes to act directly toward the center of the wheel. The hole through the shoe A fits the bolt H, but the hole for the bolt H' is elongated horizontally, so that the bolt may have some play back and forth. An arm, K, is fixed upon this shaft or bolt H' and projects horizontally outward, and is connected by a rod, L, with the lever M, by which power is 60 applied.

The inner end of the arm K has a toe, n, projecting downward, and when the outer end of the arm is drawn down it brings this toe into contact with the back of the brake-shoe A' 65 and presses it against the wheel.

The slot through which the bolt or shaft H' passes allows it to move back as the pressure is applied, and the side rods, J, draw the opposite brake-shoe A against the wheel upon 70 that side, thus gripping the wheel firmly between them. When the brake is released by lifting the arm K upward, the toe N is thrown back and strikes a lug, o, which is formed on the back of the brake-shoe A', and thus 75 draws or stands this shoe back, the slot in the shoe allowing the side bars, J, enough motion to permit the opposite shoe to fall away and leave the wheel free from pressure.

Adjusting-screws P pass through lugs which 80 project from the lower ends of the brake-shoes, and when the brakes fall away from the wheel these screws will strike the suspending links or bars E, which prevents the lower end from swinging back far enough to throw the upper 85 end in and cause it to rub against the wheel. Set-screws S S are placed in such a position that they regulate the distance that the brake falls back.

Having thus described my invention, what I 90 claim as new, and desire to secure by Letters Patent, is—

1. In a hoisting-machine brake, the shoes A A', suspended upon the bars E by the pins H H', said pins having the vertical arms I at 95 their outer ends, and the connecting-rods J, uniting them above and below the center of the wheel B, substantially as herein described.

2. In a hoisting-machine, the brake-shoes, with their suspending and uniting rods, in 100 combination with the lever K N, mounted upon the pin H', said pin passing through an

elongated opening in the brake-shoe, so as to have an independent movement, substantially as herein described.

3. In a hoisting-machine, the brake-shoes, with their suspending and uniting rods, and the lever K N, mounted upon a pin moving loosely in a slotted opening in one of the brake-shoes, in combination with a lug projecting from said shoe, so as to be engaged by the toe of the lever in its backward movement, substantially as herein described.
4. In a hoisting-machine, the brake-shoes

with their suspending and uniting rods, and the operating-lever, as shown, in combination with the screws P, when said screws pass through the lower ends of the brake-shoes, substantially as herein described.

In witness whereof I have hereunto set my hand.

WILLIAM C. WATERS.
